UNITED STATES PATENT OFFICE.

ABRAHAM DVILNSKY, OF BROCKTON, MASSACHUSETTS.

PINKING MACHINE.

Application filed January 11, 1927. Serial No. 160,443.

The present invention relates to machines for cutting leather or the like and more particularly to machines for pinking or serrating strips of leather or like material.

5 One object of the invention is the provision of a machine of the class described for dividing leather strips to form welting for boots and shoes and simultaneously pinking or serrating the edges of the resulting strips.

10 Another object of the invention is the provision of an improved cutter in a machine of the class described.

15 A further object of the invention is the provision of an improved roller coacting with the cutter.

20 Other objects of the invention will be apparent from the following description, and for a complete understanding of the invention reference is to be had thereto and to the accompanying drawings forming a part of this specification.

In the drawings:—

Fig. 1 is a front elevation of the machine embodying the present invention;

25 Fig. 2 is an enlarged view on the line 2—2 of Fig. 1;

Fig. 3 is a view on the line 3—3 of Fig. 2;

Fig. 4 is a view on the line 4—4 of Fig. 2;

30 Fig. 5 is an enlarged side view of the improved cutter;

Fig. 6 is a perspective view of a fragment of a leather strip upon which the machine operates; and

35 Fig. 7 is a perspective view of a fragment of the strip resulting from the operation of the machine.

The machine according to the present invention comprises a support or standard 10 having a bracket 11. The cutter 12 is preferably in the form of a wheel secured to a shaft 13 mounted in the bracket 11. A companion roller 14 is secured to a shaft 15 also mounted in the bracket 11. The shafts 13 and 15 have meshing gears 17 and 18, respectively. The shaft 13 is driven by a bevel gear 19 which meshes with a bevel gear 20 secured to a shaft 21 mounted in the standard 10. Any suitable means such as a belt 22 and pulley 23 may be used for driving the shaft 21 and, through the mechanisms just described, the cutter 12 and companion roller 14.

A grooved guide roller 24 is loosely mounted on a shaft 25 supported in any suitable manner as on a bracket 11 or on a separate support (not shown). This roller 24 serves

to guide the material to be treated, such as a leather strip 26 to the machine elements 12 and 14. A bracket 27 may be secured to the bracket 11 and is provided with arms 28 and 29 for holding the strip 26 against the roller 14, as shown more clearly in Fig. 3.

The cutter element comprises wheel 12 having a central bore for the bearing of the actuating shaft 13. The wheel 12 has a periphery constituting a zig-zag cutting surface 30 and an inner section of increased thickness 31 for the proper degree of rigidity. The zig-zag surface 30 consists of cutting teeth or blades 32 which extend back from the periphery of the wheel in parallel planes 33 and 34, shown in Fig. 4, for a distance greater than the thickness of the strip that is subjected to the cutting or serrating action of this cutter element. By thus arranging the cutting teeth in parallel planes, there is no crowding of the material of the strip 26 and a clean cut is accordingly obtained.

The companion roller 14 is constructed preferably as shown in Fig. 4. The roller 14 comprises a section 35 having a peripheral flange 36 and a peripheral groove 37. A ring 38 of fibre or brass or like material is mounted on the section 35 in the groove 37 and is held in place by a clamping member 39 which has a flange 40 peripherally thereof which cooperates with the flange 36 to form a circumferential groove 41. Nuts 42 and 43 may be employed for securing the roller 14 on its actuating shaft 15. It will be noted that the ring 37 is removable and may be replaced when worn, and it will be understood from this disclosure that the ring 37 is of softer material than the cutter elements 32 so that these elements remain sharp for an increased length of time.

In an application filed January 11, 1927, Ser. No. 160,444, I have shown and described a method of forming welts from strips of leather such as strip 26 shown in Fig. 6. This strip comprises an intermediate longitudinally extending rib 26^a. The strip 26 is divided into two strips 26' each of which has a marginal flange 26^b, the edge of which is serrated or pinked as at 27^c. To thus form the strips 26', the strip 26 is subjected to the action of the cutter element 12 cooperating with the companion roller 14.

As shown by Figs. 2 and 3, the strip 26 is passed between the cutter 12 and the roller 14 the coaction of which draws the strip therebetween, dividing the strip and impart-

ing to the edges thereof the pinked edges 27°. The strip 26 is guided by the roller 24 and is held in the groove 41 of the cutter element 25, companion roller 14 by the arms 28 and 29, as shown more clearly by Fig. 3. When a ribbed strip 26 is being treated, the guide arms 28 and 29 are disposed on opposite sides of the rib 26, but it will be understood that the arms 28 and 29 may be used with advantage with a strip of other cross section. The groove 41 is preferably substantially the width of the strip being treated so that strips of identical characteristics may be produced with the use of the roller 14 and the cutter element having the cutting teeth 32 as shown.

While I have shown and described the preferred embodiment of the invention, it will be understood that the disclosure is more or less illustrative of the principles of the invention and that certain changes in the construction and arrangement of parts may be made without departing from the invention as defined by the appended claims.

Having thus described the invention, what I claim and desire to secure by Letters Patent of the United States is:

1. In a machine of the class described, a rotary pinking wheel, a companion roller, said roller co-acting with said pinking wheel for drawing material therebetween for dividing said material and pinking the edges of the divided portions, means for holding said material against the roller, and means for positively driving said cutter and roller.
2. In a machine of the class described, a

rotary cutter, a companion roller having a peripheral groove, said cutter and roller co-acting to draw material therethrough and subject said material to the action of said cutter, and means for holding said material against said companion roller in said groove.

3. In a pinking machine, a pinking cutter, and a companion roller having a ring in juxtaposition with the periphery of said cutter for co-acting therewith, said ring being of softer material than that of the cutter.

4. In a pinking machine, a pinking cutter, a companion roller having a ring in juxtaposition with the periphery of the cutter for co-acting therewith, and means for removably associating said ring with said roller.

5. In a machine of the class described, a rotary cutter, and a companion roller, said cutter and roller co-acting to draw a strip of material therethrough to be subjected to the action of said cutter at the bight thereof with said roller, said roller having peripheral flanges for positioning said strip with respect to said cutter.

6. In a pinking machine, a rotary cutter comprising a pinking wheel having a central portion and a reduced peripheral portion comprising radially extending blades terminating axially of said cutter in parallel planes and having straight cutting edges terminating axially of said cutter in said parallel planes.

In testimony whereof, I hereunto affix my signature.

ABRAHAM DVILNSKY.
